UNITED STATES PATENT OFFICE.

MAHLON J. NEUMANN, OF WYMORE, NEBRASKA.

EMBROIDERED TRIMMING.

1,215,400.

Specification of Letters Patent. Patented Feb. 13, 1917.

Application filed December 13, 1910. Serial No. 597,134.

To all whom it may concern:

Be it known that I, MAHLON J. NEUMANN, a citizen of the United States, residing at Wymore, Gage county, Nebraska, have invented a certain new and useful Improvement 5 in Embroidered Trimming, of which the following is a full, clear, and exact description, such as will enable others skilled in the art to which it appertains to make and 10 use the same.

This invention relates to machine-made embroidery, and particularly to machine-made embroidery provided with what is 15 commonly termed a "Schiffli embroidery edge."

One object of my invention is to provide an embroidery edge which is so formed that the threads composing same will not separate, pull apart, fray or ravel.

20 Another object is to provide a machine-made embroidery edge which is composed of a series of festoons formed from parallel stitches arranged at approximately right angles to the length of the embroidery, and 25 means for locking the festoons together and binding said parallel stitches to the cloth so as to reinforce the cloth longitudinally and prevent the cloth or the parallel stitches from separating laterally or from fraying 30 out.

Figure 1 of the drawings illustrates a piece of Schiffli embroidery edge as it comes from the machine;

Fig. 2 shows the embroidery after the part 35 of the cloth that lies outside or beyond the edge has been removed or cut off;

Fig. 3 shows how the threads composing the edge pull apart or separate laterally after the embroidery has been used; and

40 Fig. 4 illustrates my improved embroidery.

The embroidery made on Schiffli machines is provided with an edge which is composed of a series of festoons, each of which consists of a number of parallel lock stitches 1 arranged close together and extending at approximately right angles to the length of the embroidery. Several pieces or lengths of embroidery are formed simultaneously on a 45 single piece of cloth, and after the cloth has been removed from the machine the portion A of the cloth which lies outside of or beyond the edge of the embroidery is removed by cutting the cloth adjacent to the outer 50 ends of the stitches 1 so as to separate this portion of the cloth from the embroidery,

as shown in Fig. 2. Cutting the cloth in this manner produces a raw edge, or unfinished edge, which is not capable of withstanding longitudinal strains or strains 60 lengthwise of the embroidery, so that the result is that the edge portion of the embroidery is apt to split or open up when the embroidery is bleached and finished or after the embroidery has been in use for a short 65 while, thereby causing the threads which constitute the "edge" of the embroidery to separate or pull apart laterally, as shown in Fig. 3.

Another objectionable feature of the 70 Schiffli embroidery edge is that the parallel stitches 1 which constitute the edge are often severed in the operation of removing the portion A of the cloth that lies outside of the edge, so that said stitches fray out or 75 ravel shortly after the embroidery has been in use, thus causing the embroidery to have a worn and frayed-out look.

The object of my invention is to provide an edge for embroidery which has not the 80 objectionable features of the ordinary Schiffli embroidery edge above described, and to this end I have devised an embroidery edge which is composed of a series of 85 festoons formed from parallel stitches arranged at approximately right angles to the length of the embroidery, and means for locking said festoons together and binding the stitches composing same to the cloth, thereby reinforcing and strengthening the 90 cloth longitudinally and preventing the cloth from splitting or the parallel stitches from separating laterally or from fraying out in case they are severed in the operation of cutting out the edge or separating it from 95 the cloth which lies outside of same.

Referring to Fig. 4 of the drawings which illustrates one form of my invention, 2 designates parallel stitches (preferably lock stitches) arranged close together and at approximately right angles to the length of the embroidery so as to form a series of festoons, and 3 designates the means which locks said festoons together and binds the parallel stitches to the cloth, said means also 100 reinforcing and strengthening the cloth longitudinally. Said means consists of one or more rows 3 of stitches, preferably lock stitches, that extend transversely of the 105 stitches 2 longitudinally of the edge of the 110 embroidery. I prefer to arrange the row or rows of stitches 3 adjacent to the outer

ends of the festoons which the stitches 2 form and have said rows follow the general outline of the edge of the embroidery but it is immaterial so far as my broad idea is concerned, whether this locking means follows the exact outline of the edge so long as it performs its functions, namely, locking the festoons together and binding the stitches 2 comprising same to the cloth so as to prevent 5 said stitches 2 from separating laterally or from fraying out, and also strengthening the cloth longitudinally and laterally and thus improving the appearance of the embroidery edge and giving it additional 10 weight and stiffness. The exact number of locking stitches 3 per inch is also immaterial so far as my broad idea is concerned, and as previously stated, one or more rows of said stitches can be used. I prefer to 15 form the locking stitches 3 on the same machine on which the embroidery is made and at the same time the embroidery is made by which it is to be understood that the embroidery edge is formed in the usual manner 20 on a Schiffli machine, with a needle thread and a shuttle thread for each festoon, and the longitudinal locking stitches are therefore necessarily formed of the same needle threads as the parallel edge stitches, but, if 25 desired, said locking stitches can be formed by a separate machine after the embroidery has been removed from the machine on which it is formed, and either before or 30 after the embroidery is bleached and finished.

My improved embroidery edge can be manufactured at approximately the same cost as Schiffli embroidery edge or other machine-made embroidery edges but it is a 35 decided improvement on such embroidery edges because the series of festoons which constitute the edge proper of the embroidery edge, and each of which is formed from a plurality of parallel stitches, are securely 40 locked together and bound to the cloth by one or more rows of stitches that extend 45

transversely of same and thus prevent the edge from opening up or splitting after the embroidery has been in use for a short time. Furthemore, the locking stitches prevent the 50 parallel stitches which form the festoons from fraying out or raveling in case the ends of said stitches are severed during the operation of cutting out the edge, and said locking stitches also reinforce the cloth longitudinally, improve the appearance of the 55 edge and give it more weight and firmness so that it is not so apt to tear or snag.

Having thus described my invention, what I claim as new and desire to secure by Letters Patent is:

In a strip of embroidered trimming of the Schiffli type, having festoons comprising parallel edge stitches formed of one needle thread and one shuttle thread for each festoon on the foundation fabric, the improvement which consists in a series of parallel rows of locking stitches for each festoon formed of the same threads as the parallel edge stitches in said festoon and extending 65 longitudinally throughout the festoons, transversely across the parallel edge stitches near the outer ends of said stitches, following substantially the outline of the edge of the embroidered trimming, and 70 forming a bead or purl as a wearing surface on the outer edge, said transverse locking stitches for each festoon crossing and reinforcing the meeting points of the festoons and fastening the festoons together and fastening down and binding together the parallel edge stitches, thus preventing the parallel edge stitches from separating laterally or from fraying out when the foundation 75 fabric is cut away.

In testimony whereof I hereunto affix my signature in the presence of two witnesses, this ninth day of December 1910.

MAHLON J. NEUMANN.
